United States Patent Office.

G E O R G E T E F F T, O F S A L E M, N E W Y O R K.

Letters Patent No. 76,551, dated April 7, 1868.

MUSIC-RACK.

The Schedule referred to in these Letters Patent and making part of the same.

TO ALL WHOM IT MAY CONCERN:

Be it known that I, GEORGE TEFFT, of Salem, in the county of Washington, and State of New York, have invented a new and improved Music-Rack; and I do hereby declare the following to be a full, clear, and exact description of the same, reference being hereby had to the accompanying drawings, which form and make a part of this specification.

Like letters represent and refer to like or corresponding parts.

Figure 1 is a perspective view of my said improved music-rack, showing the various parts thereof, each more fully hereinafter described and set forth.

Figure 2 is also a perspective view of my said invention, showing the same as it would appear when the leaves or folds, O, were open, as fully hereinafter described and set forth.

Figure 3 is a view of the bottom of the bed plate, A, showing the mechanism by which the leaves or folds, O, are operated, substantially in the manner and by the means hereinafter described and set forth.

Figure 4 is a cross-section through the cylinders D, D', and D'', and clearly showing the construction and operation of the same, as fully hereinafter described and set forth.

The nature of my said invention and improvements consists in so constructing a music-rack or frame, that when the same is in use, the music placed thereon may be readily turned by the person playing the instrument, without any inconvenience; substantially in the manner and by the means hereinafter described and set forth.

It also consists in the employment of the levers C, C', and C'', in connection with the cylinders D, D', and D'', each constructed, combined, and operated in the manner and for the purposes substantially as hereinafter described and set forth.

It also consists in the employment of the springs E, E', and E'', and F, F', and F'', by means of which the levers C are operated so as to turn the leaves or folds of the music-rack, substantially in the manner and for the purposes hereinafter fully described and set forth.

To enable others skilled in the art to which my invention relates to make and use the same, I will here proceed to describe the construction and operation of the same, which is as follows, to wit: A, figs. 1, 2, and 3, is the bed-plate of my said music-rack, and may be made of any wood or metal deemed best. At the rear end thereof is the upright or bar B, which is securely fastened to the said plate A by any means thought best. Around the bottom of said upright, B, are placed the cylinders D, D', and D'', constructed substantially as shown at figs. 3 and 4, in the accompanying drawings, having attached at their lower ends, and under the bed-plate A, the cog-wheels H, H', and H''. The upper cylinder D passes through both the cylinders D' and D'', and is connected at its lower end with the under cog-wheel H''. The second and middle cylinder D' is formed around the upper cylinder D, but passes through the lower cylinder D'', and is connected at its lower end with the middle cog-wheel H', while the lower cylinder D'' surrounds both the upper ones, D and D', and is connected at its lower end with the upper cog-wheel H. It is obvious that as many cylinders and wheels can be used as may be required, if constructed upon the principle and in the manner above described. Upon the under side, and at about the centre of the bed-plate A, I attach, by means of a pivot, I, the levers C, C', and C'', or their equivalents, the said pivot I allowing them to work freely both ways. The rear ends of each of the said levers C, C', and C'', are notched so as to correspond with the cog-wheels, H, H', and H'', into which they work, for the purpose of turning the said cylinders D, D', and D''. At the other ends of the said levers C, C', and C'', are attached the thumb-pieces J, J', and J'', which pass through the bed-plate A, and by means of which the said levers are worked, which, in their turn, operate the said cylinders D, D', and D''. E, E', and E'', are suitably-constructed springs, securely fastened at one end to the bottom of the bed-plate A, and which press against and operate the said levers C, C', and C'', substantially as hereinafter described and set forth. F, F', and F'', are also springs which are for the purpose of holding the levers C, C', and C'', in their proper place and position when the same are set in the manner and for the purposes hereinafter described. The said springs F, F', and F'', are also operated by means of thumb-pieces K, K', and K'', which pass through the said bed-

plate A, in the manner and for the purposes, hereinafter described. To each of the cylinders surrounding the upright or bar B, is attached a suitably-shaped frame or device, into which the music may be placed. Any construction thereof may be adopted that will best answer the required purpose. The various parts of my said improved music-rack may be made of any material deemed best, and of such size, strength, and quality as future experiment may indicate.

When it is desired to use my said invention for the purpose which it is intended, the manner of operating is as follows: The music desired to be played is placed in the rack or frame which is attached to the cylinders, the said cylinders are then set by means of the levers C, C', and C'', which are held in the position they are set by means of the springs F, F', and F'', which catch in slots cut on the under side of the said levers, as shown at fig. 3 in the accompanying drawings. When it is desired to turn the first leaf of the music, the thumb-piece K is pressed downward, which pushes the spring F out of the slot in the lever C; the spring E, then-acting upon the said lever, presses it back, thereby turning the cylinder D, to which the frame is attached in which the music is placed. This same operation with the second lever will turn the second leaf of the music, and so on, as many levers may be used as desired, according to the number of leaves desired to turn. By this means I am enabled to construct a music-rack, in which the music placed therein may be turned without any inconvenience to the player, as a slight pressure upon the thumb-pieces K, which are designed to be placed immediately in front of the player, will turn the different leaves of the music, substantially as hereinbefore described and set forth.

Having thus described the nature of my said invention and improvements, what I claim as my invention, and desire to secure by Letters Patent of the United States, is—

1. An improved music-rack or machine for turning music, constructed in the manner and for the purposes substantially as herein described and set forth.

2. I claim the notched levers C, C', and C'', and the cog-wheels H, H', and H'', and the cylinders D, D', and D'', in combination with and operating the leaves or folds O of a music-rack or frame, substantially as hereinbefore fully described and set forth.

3. I claim the upright or bar B, and the cylinders D, D', and D'', and levers C, C', and C'', in combination with a music-rack or frame, substantially as herein fully described and set forth.

4. I claim the combination of the levers C, C', and C'', operated by the springs E, E', and E'', and F, F', and F'', with the cog-wheels H, H', and H'', cylinders D, D', and D'', and upright or bar B, each being constructed and operated in the manner and for the purposes substantially as herein fully described and set forth.

In testimony whereof, I have hereunto set my hand, this 9th day of April, 1867.

GEORGE TEFFT.
